UNITED STATES PATENT OFFICE.

HARRY W. SMITH, OF NEWARK, NEW JERSEY.

ELECTRIC CAR.

SPECIFICATION forming part of Letters Patent No. 399,092, dated March 5, 1889.

Application filed October 26, 1888. Serial No. 239,220. (No model.)

To all whom it may concern:

Be it known that I, HARRY W. SMITH, a citizen of the United States, residing at Newark, in the county of Essex and State of New Jersey, 5 have invented certain new and useful Improvements in Electric Cars or Vehicles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide an 15 electric car such as have magnets thereon or beneath them adapted to affect certain armatures on the railway to produce a continuous metallic circuit from the electric generator to the motor on the car, which will not be 20 liable to be interfered with, damaged, or otherwise be rendered ineffective by the said magnets attracting and carrying by direct contact nails, hoops, and other magnetizable matter commonly found in the streets of a city. 25 The invention consists in the improved electric car, and in the combinations and arrangements of parts, substantially as will be hereinafter set forth, and finally embodied in the clauses of the claim.

30 Referring to the accompanying drawings, in which like letters of reference indicate corresponding parts in each of the several figures, Figure 1 indicates a car in side elevation having my improvement attached; and Fig. 2 is a section of the same, taken on line x. Fig. 3 is a horizontal section showing the construction of the end of the magnet-carrier, taken on line y. Fig. 4 is a detail illustrating the 35 means employed for suspending certain contact-brushes; and Fig. 5 is a longitudinal section of the same, taken on line z.

In said drawings, a indicates the body of a car or vehicle of any suitable construction, more especially such as are employed on the 45 tram or rail ways, and particularly the electric railway described in a contemporaneous application, Serial No. 285,400, filed by me on the 14th day of September, 1888. Beneath said car is arranged, preferably by being suspended from the car-wheel axles b b, a magnet holder or carrier, c. This consists, preferably, of two plates, preferably planks or boards,

d d, held apart and connected at the opposite ends by guard-blocks e e, as indicated more clearly in Fig. 3. Said guard-blocks serve as 55 fenders, and are formed on an incline, as at e', on their under side, so that they will ride over stones or other obstacles found on the railway. The said magnet-holder is movable on its 60 bearings on the axles, to allow of vertical play when thus riding over obstructions, the bearing-box f being slotted or provided with a vertical oblong passage, f', through which the car-axle extends. An adjusting-screw, g, in each of the boxes, serves to raise or lower the 65 holder or carrier c with relation to the railway.

The lower side of the holder c is provided with a sheet of brass or other suitable non-magnetic protector, c', for the magnet, which 70 lies between the railway and magnet, and will serve to prevent nails or other magnetic material from being attracted from the road bed or way and being carried in direct contact by the magnets. The upper side of the holder 75 is also covered, as at h, to prevent dust or moisture from entering the magnet-chamber c² thus formed.

The magnets i i' may be permanent or electro-magnets; but I prefer to employ both 80 kinds, as shown, i indicating the electro-magnets and i' the permanent magnets. The latter secure a first impulse or movement of the armatures on passing the car upon the track to secure the continuous circuit, while the latter are more durable and less expensive. Said 85 magnets are arranged in the holder or carrier in any suitable manner and the electro-magnets are connected together and to the motor j by wires j.

At suitable points in the length of the carrier are arranged brushes or contact-points k, adapted to engage the plates l l of the railway, substantially as in the manner described in a contemporaneous application, filed September 14, 1888, Serial No. 285,400. Said 95 brushes are arranged in passages m, Figs. 4 and 5, formed in the carrier or holder, but separated from the magnet-chamber c² by partitions m' m'. At their lower ends the brushes 100 extend through said passages to engage the plates l, and at their upper ends they project above the holder or carrier and are adjustably held by spring-arms n, which latter al-

low vertical play to the brushes to provide for inequalities on the roadway, and for obstructions such as have been heretofore referred to.

By loosening the set-screws *o* the plates comprising the brush may be raised or lowered with reference to the spring-arms *n*, as may be desired.

Having thus described the invention, what I claim as new is—

- 1. The improved electric car combining with the body of a car a magnet-holder, magnets, and a plate of non-magnetic metal arranged between the magnet and railway when the car is in operation, substantially as and for the purposes set forth.
- 2. The improved electric car combining with the car-body a magnet-holder consisting of boards or plates *d d*, provided with fenders at the ends and covered top and bottom with non-magnetic material and magnets arranged in said holders, substantially as and for the purposes set forth.
- 3. The improved electric car or vehicle combining with the car-body a magnet-holder arranged beneath the body of the car, and a series of magnets, including both electro-magnets and permanent magnets, substantially as and for the purposes set forth.
- 4. The improved electric car combining with the car-body axles *b b*, a magnet-holder movably arranged on said axles, and magnets, substantially as and for the purposes set forth.
- 5. The improved electric car combining with the car-body an adjustable magnet-holder suspended from the axles thereof, and magnets, substantially as and for the purposes set forth.
- 6. The improved electric car combining with

the car-body an electric motor and magnets, a magnet-holder inclosing said magnets, and a brush or brushes extending through said holder to engage the track or way, substantially as and for the purposes set forth.

7. The improved electric car combining with the car-body a series of inclosed magnets arranged beneath the body of the car to attract armatures in the railway, substantially as and for the purposes set forth.

8. In combination, in a car having an electromotor, plates *d d*, cover *h*, and partitions *m' m'*, forming brush-passages, brushes arranged in said passages and adapted to engage a conductor in the railway and transmit the current therefrom and connected with said motor, substantially as and for the purposes set forth.

9. The improved electric car combining with the car-body a magnet-holder, brushes adjustably arranged with relation to said holder, and springs secured on said holder and to said brushes, substantially as set forth.

10. The improved electric car combining therein a magnet-holder and magnets, and brushes arranged on said holder to engage the conducting agents on the road or way, said brushes being carried by springs to allow an automatic adjustment relative to said way, substantially as and for the purposes set forth.

In testimony that I claim the foregoing I have hereunto set my hand this 24th day of October, 1888.

HARRY W. SMITH.
